UNITED STATES PATENT OFFICE

2,664,825

MULTICYLINDER PUMPING SYSTEM

Leonard E. Sundstrom, Litchfield, Nebr.

Application January 29, 1952, Serial No. 268,851

2 Claims. (Cl. 103—46)

1

This invention relates to a multi-cylinder pumping system and has for its primary object to facilitate the lifting of water from a well to the surface.

Another object is to utilize the columns of water standing in a pair of well pipes to actuate a pump located adjacent the bottom of the well.

Still another object is to insure the smooth flow of water from the pumping system and avoid the usual pulsations accompanying the employment of a reciprocating pump.

The above and other objects may be attained by employing this invention which embodies among its features a pair of spaced parallel water filled well pipes extending into a well, a pair of lower pumping cylinders carried by the well pipes adjacent the bottom of the well, a check valve connected to the bottom end of each lower cylinder below the level of the water in the well for admitting water into its respective cylinder, a pair of lower pistons working in the lower cylinders, a lower walking beam mounted between the lower cylinders to oscillate adjacent the check valves, said lower walking beam being operatively connected to the lower pistons, an upper pair of pump cylinders carried by the well pipes adjacent the top of the well, an upper pair of pistons working in the upper pair of cylinders, an upper walking beam extending between the upper cylinders above the upper ends thereof and operatively connected with the upper pistons, means carried by the upper walking beam above the well for positively oscillating it and reciprocating the upper pistons in the upper cylinders, and by water in the well pipes, reciprocating the lower pistons in the lower cylinders, and means connected to the lower cylinders for delivering water entering them through the check valves to the upper end of the well.

Other features include a conduit connected to one of the lower cylinders below the piston working therein and to the second lower cylinder above the piston working therein, a second conduit connected to the second lower cylinder below the piston working therein and to the first lower cylinder above the piston working therein, check valves in said conduits adapted to open under the pressure of water expelled from the cylinders into the conduits, and means carried by the well pipes adjacent the top of the well and connected to said conduits through the well pipes through which water is delivered at the top of the well.

In the drawings,

2

Fig. 1 is a fragmentary sectional view through a pair of well pipes showing the upper and lower cylinders and pistons therein, it being understood that the lower ends of the well pipes carrying the lower cylinders are disposed adjacent the bottom of a well and below the water level therein.

Fig. 2 is a vertical sectional view taken substantially along the line 2—2 of Fig. 1.

Fig. 3 is a vertical sectional view taken substantially along the line 3—3 of Fig. 1.

Fig. 4 is a vertical sectional view taken substantially along the line 4—4 of Fig. 1.

Fig. 5 is a side view partially in section of a modified form of the invention, and

Fig. 6 is a view similar to Fig. 5 of a further modification of the invention.

Referring to the drawings in detail a pair of spaced parallel well pipes 10 and 12 are provided adjacent their lower ends with pumping cylinders 14 and 16 respectively. The lower ends of the pumping cylinders 14 and 16 are respectively equipped with foot valves 18 and 20 which are disposed adjacent the bottom of the well and below the water level therein so that as the pistons within the cylinders 16 reciprocate water will be drawn into the cylinders through the foot valves. While it is not absolutely essential to the operation of the device it is preferred that the foot valves 18 and 20 be of the ball check type having springs which advance the balls against the valve seats.

Carried by the upper ends of the well pipes 10 and 12 are upper pumping cylinders 22 and 24 respectively, the upper ends of which open into a cap 26 having a bottom 28 which extends between the cylinders 22 and 24 and forms a support for a bearing 30 the purpose of which will be more fully hereinafter described. Mounted for rocking motion in the bearing 30 is a spherical bearing member 32 carrying oppositely extending arms 34 and 36, the ends of which remote from the bearing member 32 are pivotally coupled to piston rods 38 and 40 respectively which in turn are respectively connected to pistons 42 and 44 which work respectively in the cylinders 22 and 24 as will be readily understood upon reference to Fig. 1. A radially extending arm 46 is carried by the bearing member 32 and is connected through a suitable link 48 to a lever 50 which is pivotally supported at 52 on a bracket 54 carried by the cover 26. It will thus be seen that as the lever 50 is moved about its pivot 52, the arm 46 will be oscillated thereby causing the bearing member 32 and arms 34 and 36 to oscillate in the manner of a walking beam.

Carried by and extending between the lower cylinders 14 and 16 is a bearing 56 in which a bearing member of spherical formation 58 is mounted to oscillate. Like the bearing member 32, the bearing member 58 is provided with oppositely extending arms 60 and 62 which move in arcuate paths within cylinders 14 and 16 respectively and are connected through the medium of connecting rods 64 and 66 with pistons 68 and 70 which work in the cylinders 14 and 16 above the walking beam comprised of the bearing member 58 and the arms 60 and 62. It will thus be seen that columns of water standing within the pipes 10 and 12 between the pistons 42 and 68 and between the pistons 44 and 70 will cause the pistons in their respective cylinders to move in unison.

Formed in the cylinder 14 are longitudinally spaced ports 72 and 74 which are located respectively below and above the length of stroke of the piston 68, and formed in the cylinder 16 and extending through the side thereof in longitudinally spaced parallel relation are ports 76 and 78 which are respectively located below and above the limit of the stroke of the piston 70 in the cylinder 16. It will thus be seen that water entering the cylinder 14 through the foot valve 18 thereof on the upstroke of the piston 68 will be expelled from said cylinder through the port 72 upon the down stroke of the piston 68. Likewise water admitted to the cylinder 16 through the foot valve 20 during the up stroke of the piston 70 will be expelled through the port 76 upon the down stroke of the piston 70.

Mounted adjacent the well bottom near the cylinders 14 and 16 is a water box designated generally 71 which comprises a front wall 79, a rear wall 80, side walls 82 and top and bottom walls 84. This water box forms a hollow rectangular structure which is separated by a partition wall 86 into separate chambers or compartments A and B. A pipe nipple 87 communicates through the port 72 with the cylinder 14 and extends through the wall 79 of the water box 71 and into the chamber B, and carried by the end of the pipe nipple 87 within the chamber B is a check valve 88 which is designed to admit water from the cylinder 14 into the chamber B, but arrest the discharge of water through the nipple 87 into the cylinder 14. A pipe nipple 89 communicates with the cylinder 14 through the port 74 and opens into the chamber A as will be readily understood upon reference to Figs. 2 and 4. A pipe nipple 90 establishes communication between the cylinder 16 below the piston 70 and the chamber A and is equipped with a check valve 92 (Fig. 4) which prevents the discharge of liquid from the chamber A into the cylinder 16. A pipe nipple 94 establishes communication through the port 78 between the cylinder 16 above the piston 70 and the chamber B so that as the pistons 68 and 70 reciprocate in their respective cylinders 14 and 16, on the down stroke of the piston 68 in the cylinder 14, water will be forced through the check valve 88 and into the chamber B, to be discharged through the nipple 94 and port 78 into the cylinder 16 above the piston 70 working therein. Simultaneously through the walking beam coupling between the pistons 68 and 70, the upward movement of the piston 70 will fill the cylinder 16 with water through the check valve 20, so that upon the down stroke of the piston 70, the water contained in the cylinder 16 will be expelled through the pipe nipple 90 and check valve 92 into the chamber A. The water expelled from the chamber A 75 and forcing said water through the pipe nipple

will find its way through the pipe 89 and the port 74 into the well pipe 10 above the cylinder 14 while the water which is expelled from the chamber B will find its way through the pipe nipple 94 into the well pipe 12 above the cylinder 16. The water thus expelled from the chambers A and B will form water columns in the well pipes 10 and 12 beneath the pistons 42 and 44 in the cylinders 22 and 24 respectively.

A water box designated generally 96 is carried by the well pipes 10 and 12 adjacent the cylinders 22 and 24 near the upper end of the well hole, and comprises front and back walls 98 and 100 respectively and side walls 102, 104 and top and bottom walls 106. A horizontally extending partition wall 108 extends across the water box 96 between the end walls 102 and 104 adjacent the top 106 to define a chamber E and a partition wall 110 cooperates with the horizontal partition wall 108 in separating the lower portion of the water box 96 into separate compartments C and D. A water discharge pipe 112 communicates with the compartment E through the wall 104 of the water box 96 and communication between the compartment E and the compartments C and D is established by check valves 114 and 116 respectively which prevent the discharge of water from the compartment E into the compartments C and D while permitting the flow of water from the compartments C and D into the compartment E for subsequent discharge through the discharge pipe 112. Establishing communication between the compartment C and the cylinder 22 below the piston 42 is a pipe nipple 118 carrying at its end within the compartment C a check valve 120 which prevents the egress of water from the compartment C into the cylinder 22 and a similar pipe nipple 122 establishes communication between the cylinder 24 and the compartment D below the piston 44, and like the pipe nipple 118 is equipped with a check valve 124 which prevents the discharge of water from the compartment D into the cylinder 24. A pipe nipple 126 establishes communication between the compartment D and the cylinder 22 above the piston 42 and a similar pipe nipple 128 establishes communication between the compartment C and the cylinder 24 above the piston 44 working therein.

In the preferred form of the invention, the pipe 118 has communicating therewith a priming valve 130 which opens into the chamber C while the pipe 122 is likewise equipped with a priming valve 132 which opens into the chamber D. Each of these valves is equipped with a turning rod 133 and a handle 134 by means of which the valves may be turned to open or closed position.

In use, with water standing in the pipes 10 and 12 between the cylinders 22 and 14 and 24 and 16, it will be evident that when the lever 50 is rocked about its pivot 52, the walking beam at the upper end of the well will reciprocate the pistons 42 and 44 in their respective cylinders 22 and 24 so that the water within the pipes will react against the pistons 68 and 70 to cause them to reciprocate in their respective cylinders 14 and 16. As the water is drawn into the cylinder 14 through its respective check valve 18, the piston 70 descending in its respective cylinder 16 will force the water below it into the chamber A through the check valve 92, thus causing the water standing in the chamber A to be discharged through the pipe 89 into the pipe 10 so that it will flow upwardly, thus creating pressure on the column of water standing within the pipe 10 and forcing said water through the pipe nipple

118 and check valve 120 into the compartment C. With the end of the cylinder 22 above the piston 42 working therein filled with water, the water forced thereinto through the check valve 124 will find its way through the check valve 116 into the compartment E to be discharged through the pipe 112. As the piston 44 moves downwardly within its cylinder 24, pressure will be exerted on the piston 78 to force it downwardly and thereby cause the water which has been drawn into the cylinder 16 through the check valve 20 to be expelled through the port 76 and pipe 90 and the check valve 92 into the chamber A. With the chamber A filled with water, it will be evident that the water flowing thereinto through the check valve 92 will force water out thereof through the pipe 89 into the cylinder 14 and pipe 10 upwardly and into the chamber C through the pipe 118 and check valve 120 so that the water thus drawn into the cylinder 16 through the check valve 20 will be eventually discharged from the chamber E and discharge pipe 112 at the top of the well.

In the modified form of the invention illustrated in Fig. 5, a pair of well pipes 135 and 136 are equipped at their lower ends with cylinders 137 and 138 having pistons 140 and 142 working therein. The cylinders 137 and 138 are provided at their lower ends with foot valves similar to the foot valves 18 and 20 previously described and the pistons are coupled through the medium of long connecting rods 144 and 146 with opposite ends of a walking beam designated generally 148 which is mounted in a bearing 150 carried by the pipes 135 and 136 adjacent the upper end of the well. These pipes are coupled through conventional couplings such as elbows 152 and 154 with horizontal pipes 156 and 158 respectively which in turn are coupled through the medium of elbows 160 and 162 with pump cylinders 164 and 166 located at any convenient place above the surface of the ground. Pistons 168 and 170 work within the cylinders 164 and are connected through the medium of connecting rods 172 and 174 with a walking beam 176 which works in a suitable bearing 178 carried at the upper ends of the cylinders 166. The walking beam is equipped with a laterally extending arm 180 which may be coupled to a suitable linkage designated generally 182 by means of which the walking beam may be made to rock in its bearing 178 to reciprocate the pistons 168 and 170 within their respective cylinders 164 and 166. A water box designated generally 184 and conforming to the structure of the water box 11 is connected to the cylinders 137 and 138 substantially as previously described and a water box designated generally 186 conforming in construction to the water box 96 is connected to the cylinders 164 and 166 substantially as previously described. Like the water box 96, the water box 186 is equipped with a discharge pipe 188 through which water pumped by the pumping mechanism is discharged for subsequent use. The structure illustrated in Fig. 5 operates in a manner corresponding to the operation of the structure illustrated in Figs. 1 through 4 inclusive with the pistons 140 and 142 being actuated by the movement of the columns of water within the pipes 156 and 158.

In the further modification of the invention illustrated in Fig. 6 a pair of well pipes 190 and 192 are provided at their lower ends with cylinders 194 and 196 respectively in which pistons 198 and 200 are mounted to reciprocate. A water box designated generally 202 is provided

with partition walls 204 and 206 which separate the box into compartments F, G and H. The compartment F has connected thereto a single well pipe 208 which leads to the bottom of the well and carries a conventional foot valve (not shown). The lower ends of the cylinders 194 and 196 are provided with foot valves and extending between the lower ends of the cylinders 194 and 196 and the water box 202 and communicating respectively with the compartments G and H therein are pipe nipples 210 and 212 having check valves 214 and 216 respectively disposed within the compartments G and H which are so arranged as to prevent the egress of water from their respective compartments into the cylinders 194 and 196 on the down stroke of the respective pistons. Pipe nipples 215 and 217 connect the cylinders 194 and 196 to the compartments G and H respectively above the ends of the pistons 198 and 200. The upper ends of the well pipes 190 and 192 are coupled through ports 218 and 220 to a discharge pipe 222 through which water pumped by the pistons 198 and 200 is discharged for use. A walking beam 224 is rockably mounted in a bearing 226 carried by the pipes 190 and 192 at the upper ends thereof and opposite ends of the walking beam 224 are coupled to connecting rods 228 and 230 which in turn are connected to the pistons 198 and 200 respectively so that as the walking beam is rocked in its bearing 226, the pistons will be reciprocated in their respective cylinders. An arm 232 is carried by the walking beam 224 and extends laterally therefrom and is coupled to a suitable actuating linkage 234 by means of which the walking beam may be rocked and the pistons 198 and 200 reciprocated in their respective cylinders 194 and 196.

With water standing in the well pipe 208 above the foot valve thereof and filling the compartment F it will be evident that as piston 198 moves upwardly in its cylinder 194 water will enter the cylinder from the chamber F through the foot valve of cylinder 194. Reaching the upper end of its stroke the piston starts to descend against the column of water contained therein and forces the water into the compartment G. With the compartment G filled, the water flowing thereinto through pipe nipple 210 will force water out of the compartment G through pipe nipple 214 and into the column of water standing in the well pipe 190 to cause water to be discharged through the port 218 at the upper end of said well pipe. Owing to the fact that water is forced into the well pipe 190 during the downstroke of the piston 198 and is lifted in the well pipe 190 during the upstroke of the piston, it will be evident that a substantially continuous flow of water through the discharge port 218 will result.

While in the foregoing there has been shown and described the preferred embodiment of this invention it is to be understood that minor changes in the details of construction, combination and arrangement of parts may be resorted to without departing from the spirit and scope of the invention as claimed.

What is claimed is:

1. In a multi-cylinder pumping system a pair of spaced parallel water filled well pipes extending into a well, a pair of lower pump cylinders carried by the well pipes adjacent the bottom of the well, a check valve connected to the bottom end of each lower cylinder below the level of the water in the well for admitting water

75 into its respective cylinder, a pair of lower pis-

tons working in the lower cylinders, a lower walking beam mounted between the lower cylinders to oscillate adjacent the check valve, said lower walking beam being operatively connected to the lower pistons, an upper pair of pump cylinders carried by the well pipes adjacent the top of the well, an upper pair of pistons working in the upper pair of cylinders, an upper walking beam extending between the upper cylinders above the upper ends thereof and operatively connected with the upper pistons, means carried by the upper walking beam above the well for positively oscillating it and reciprocating the upper pistons in the upper cylinders and by the water in the well pipes reciprocating the lower pistons in the lower cylinders, a conduit connected to one of the lower cylinders below the piston working therein and to the second lower cylinder above the piston working therein, a second conduit connected to the second lower cylinder below the piston working therein and to the first lower cylinder above the piston working therein, check valves in said conduits adapted to open under the pressure of water expelled from the cylinders into the conduits, an elongated chamber having a discharge opening extending therethrough, a third conduit connected to one of the upper cylinders below the piston working therein and to the second upper cylinder above the piston working therein, a fourth conduit connected to the second upper cylinder below the piston working therein and to the first mentioned upper cylinder above the piston working therein, check valves in said conduits for arresting the flow of water downwardly therethrough, the upper ends of the upper cylinders opening into the chamber, and check valves within the chamber and operatively connected to the cylinders to arrest the flow of water from the chamber into the cylinders.

2. In a multi-cylinder pumping system a pair of spaced parallel water filled well pipes extending into a well, a pair of lower pipe cylinders carried by the well pipes adjacent the bottom of the well, a check valve connected to the bottom end of each lower cylinder below the level of the water in the well for admitting water into the respective cylinder, a pair of lower pistons working in the lower cylinders, a walking beam mounted between the lower cylinders to oscillate

5 adjacent the check valves, said lower walking beam being operatively connected to the lower pistons, an upper pair of pump cylinders carried by the well pipes adjacent the top of the well, an upper pair of pistons working in the upper pair of cylinders, an upper walking beam extending between the upper cylinders above the upper ends thereof and operatively connected with the upper pistons, means carried by the upper walking beam above the well for positively oscillating it and reciprocating the upper pistons in the upper cylinders and by the water in the well pipes reciprocating the lower pistons in the lower cylinders, a conduit connected to one of the lower cylinders below the piston working therein and to the second lower cylinder above the piston working therein, a second conduit connected to the second lower cylinder below the piston working therein and to the first lower cylinder above the piston working therein, check valves in said conduits adapted to open under the pressure of water expelled from the cylinders into the conduits, an elongated chamber having a discharge opening extending therethrough, a third conduit connected to one of the upper cylinders below the piston working therein and to the second upper cylinder above the piston working therein, a fourth conduit connected to the second upper cylinder below the piston working therein, and to the first mentioned upper cylinder above the piston working therein, check valves in said conduits for arresting the flow of water downwardly therethrough, the upper ends of the upper cylinders opening into the chamber, check valves within the chamber operatively connected to the cylinders to arrest the flow of water from the chamber into the cylinders.
